UNITED STATES PATENT OFFICE.

CHARLES E. GODLEY, OF DETROIT, MICHIGAN, ASSIGNOR TO EDMUNDS AND JONES CORPORATION, OF DETROIT, MICHIGAN, A CORPORATION OF NEW YORK.

PARKING LAMP.

Application filed March 31, 1923. Serial No. 628,998.

To all whom it may concern:

Be it known that I, CHARLES E. GODLEY, a citizen of the United States, and residing at Detroit, in the county of Wayne and State 5 of Michigan, have invented a new and Improved Parking Lamp, of which the following is a specification.

This invention relates to electric lamps which are mounted on the left rear fenders 10 of motor vehicles, usually at the highest point thereof, and are provided with front and rear lenses of different colors in order to indicate the positions of such vehicles; and the object of this invention is to produce a lamp of this character which can be assembled and disassembled without the use 15 of tools, whose metallic parts shall all be completely machine-made, and which will permit the replacement of the light bulb 20 with the least amount of labor.

This invention is illustrated in the accompanying drawing in which Fig. 1 is a front elevation of this improved parking lamp. Fig. 2 is a section on the line 2—2 of Fig. 25 1. Fig. 3 is a plan of the pedestal portion of this lamp. Fig. 4 is a side elevation of the upper end of the pedestal. Fig. 5 is a front elevation of this upper end with a connector sleeve in position. Fig. 6 is a 30 section on the line 6—6 of Fig. 1. Fig. 7 is a front elevation of the lower portion of the lamp body. Fig. 8 is an inside elevation of a lens ring. Fig. 9 is a perspective view of a connector bar. Fig. 10 is a plan 35 of a connector plug.

Similar reference characters refer to like parts throughout the several views.

As stated above, each of the metallic parts 40 of this lamp are machine-made, that is, they are stamped and drawn to size ready for assembling and these parts are put together without the use of screws or keys. Each part interlocks with the adjacent parts and is spring-held in position to prevent rattling.

The barrel shaped body 1 of the lamp has its ends closed by the lens rings 2 and the lenses 3 supported thereby. I prefer to secure the lenses in position in the rings by 50 pressing the outer edges 4 thereof onto the glass. The cylindrical rings are formed with holes to permit the ears 5 of the springs 6 to project, which ears engage the inclined inner surfaces of the body at its ends and thus hold the lens rings and lenses in posi-

tion. I prefer to form a small bulge 7 at each end of the body to facilitate the introduction of these ears 5.

The pedestal 8 is formed with a base flange 9, with an inwardly extending radial flange 10 at its upper end, and with the upwardly projecting cylindrical flanges 11. At the middle portion of these cylindrical flanges 11 are the small ears 12 which are adapted to extend into the notches 13 formed in the circular flange 14 at the bottom of a shallow circular recess in the lower side of the body 1 of the lamp. The upper end of the pedestal is formed to extend up into this recess as shown in Fig. 2.

A connector sleeve 16 is adapted to slide up within the cylindrical flanges 11 and is formed with a radial circumferential flange 17 at its lower end which supports a coil spring 18. This spring presses against the lower side of the flange 10 of the pedestal. The connector sleeve is formed with bayonet slots 19 to receive the pins 20 on the base 21 of the light bulb 22. This sleeve is also formed with short inclined slots to permit the inclined upper ends 24 of the connector bars 25 to project through. The lower ends 26 of these bars are bent inward to limit the downward movement of the well known connector plug 27 which is of insulating material and has a spring held contact pin 28 at its upper end to engage the contact 29 on the base 21 of the light bulb and has a screw 30 at its lower end to secure the conductor wire 32. The plug is also formed with longitudinal grooves 33 to receive the bars 25.

To assemble the lamp, the spring 18 is placed on the connector sleeve 16 and that is slipped into the flanges 11 of the pedestal from below. The connector bars are then positioned with the inclined ends 24 above the flange 10 of the pedestal and between the flanges 11, and the plug 27 is pushed down into the sleeve 16 from above. The light bulb may now be inserted. The assembled lenses and lens rings are attached to the body and that is then so placed on the pedestal that the ends 24 of the connector 95 25 pass through the notches 13, after which the body is turned to the right one fourth rotation. The flange 14 of the body will slide under the inclined ends 24 until the notches 13 register with the ears 12 on the pedestal which will prevent the body from turning back except under considerable pressure. When 100 105 110

a light bulb is to be replaced the body is turned one fourth rotation in either direction to bring the notches 13 into registration with the inclined ends 24 of the connector bars when the body may be lifted off the pedestal.

The base flange 9 must be shaped to fit its support but all the other parts of the lamp may be interchangeable. The proportions 10 and details however may all be changed by those skilled in the art without departing from the spirit of my invention as set forth in the following claims:

I claim:

15 1. A lamp comprising a body and a pedestal, the body being barrel shaped with lenses in its ends and having a circular recess intermediate its ends and a hole at the middle of the recess, the pedestal having a circular 20 upper end adapted to fit said recess, a connector sleeve mounted in the pedestal and extending into the hole in the body, engaging members mounted in the sleeve and engaging the body to secure the body to the pedestal, and resilient means to hold the sleeve in 25 position.

2. A lamp comprising a body and a pedestal, the body and pedestal having interfitting parts, resilient means embodying a 30 spring, a connector sleeve and connector bars for securing the body to the pedestal, and lenses for closing the ends of the body.

3. A lamp comprising a barrel-shaped body, lenses and lens rings for closing the 35 ends of the body, said body having a circular depression intermediate its ends, a pedestal having an upper end adapted to fit said depression, a connector sleeve mounted in the pedestal and extending into the body and adapted to receive a light bulb at its inner 40 end, and means including a spring and inclined members projecting from the connector sleeve for detachably securing the body to the pedestal.

4. A lamp comprising a body, having a tapering open end, a lens for the open end of the body, a lens ring to support the lens and having a portion extending into the body, said portion having a plurality of circumferential slots, and a plurality of resilient 50 projections extending through said slots to engage the tapering inner surface of the end of the body to secure the lens in position.

5. In a lamp, the combination of a body 55 having open ends and a circular depression intermediate its ends, lenses and lens rings to close the open ends, said body being formed with a circular hole concentric with said depression and with radial slots extending from said hole, a pedestal having an upper portion adapted to enter the depression in the body and also having a notched circular flange adapted to extend into the hole in the body, a connector sleeve mounted 60 in the cylindrical flanges of the pedestal and

a spring to tension the sleeve, and inclined projections extending through slots in the sleeve between the notches in the flange of the pedestal and adapted to pass through the notches in the circular depressed portion of the body and to lock the body to the pedestal when they are turned relative to each other after the inclined projections have been positioned.

6. In a clamp, the combination of a body 75 having open ends and a circular depression intermediate its ends, lenses and lens rings to close the open ends, said body being formed with a circular hole concentric with said depression and with radial slots extending from said hole, a pedestal having an upper portion adapted to enter the depression in the body and also having a notched circular flange adapted to extend into the hole in the body, a connector sleeve mounted 80 in the cylindrical flanges of the pedestal and a spring to tension the sleeve, and inclined projections extending through slots in the sleeve between the notches in the flange of the pedestal and adapted to pass through 85 the notches in the circular depressed portion of the body and to lock the body to the pedestal when they are turned relative to each other after the inclined projections have been positioned, said body and pedestal being 90 kept from turning by a projection on one and a recess in the other to receive said projection when the body and pedestal have been turned.

7. A lamp comprising a body and a pedestal, the body and the pedestal having interfitting parts, and resilient means to secure the body to the pedestal comprising resiliently mounted inclined members carried by 100 the pedestal to engage the body.

8. A lamp comprising a supporting member, a lamp socket slidably mounted thereon, a body detachable from the supporting member and provided with a light-emitting opening and having another opening through which the lamp socket extends into the body, the body being rotatable with respect to the supporting member, a spring tending to slide the socket in a direction away from the body, and single means associated with the socket for normally clamping the body to the supporting member and for limiting the sliding of the socket under the force of said spring when the body is detached from the supporting member.

9. A lamp comprising a body and a pedestal, one having a circular depression and an opening at the center thereof and the other an apertured circular portion fitting the said depression, a connector sleeve mounted in the pedestal and extending into the body and adapted to receive a light bulb, and resilient means to secure the body to the pedestal upon a partial rotation of the body on the pedestal.

10. A lamp comprising a body and a pedestal, one having a circular depression and an opening at the center thereof and the other an apertured circular portion fitting the said depression, a connector sleeve slidably mounted in the pedestal and extending into the body and adapted to receive a light bulb, a spring to restrain the movement of the sleeve into the body, and means attached to said sleeve to secure the body to the pedestal upon a partial rotation of the body on the pedestal. 10

CHARLES E. GODLEY.
